UNITED STATES PATENT OFFICE.

WILLIAM KEATING, OF NEW YORK, N. Y.

DOOR-LATCH.

No. 920,478.

Specification of Letters Patent.

Patented May 4, 1909.

Original application filed April 10, 1908, Serial No. 426,218. Divided and this application filed August 3, 1908.
Serial No. 446,586.

To all whom it may concern:

Be it known that I, WILLIAM KEATING, a citizen of the United States, and a resident of the city of New York, in the county of 5 New York and State of New York, United States of America, have invented certain new and useful Improvements in Door-Latches, of which the following is a specification.

10 My invention relates to an improved door latch which is especially adaptable for use with sliding doors such as are commonly used in conjunction with elevators, and its object is to improve upon devices of this class 15 and to provide a latch which will have no portion projecting beyond the edge of a door when the latter is open.

My invention further consists in an arrangement for causing the movement of the 20 door to actuate the latch mechanism so that its action is automatic.

The invention resides in the construction and arrangement of parts which I will describe in the following specification, the 25 novel features of which will be set forth in appended claims.

In a former application for patent, Serial Number 426,218, filed by me on the 10th of April, 1908, the present invention was 30 closed, and the subject-matter of the present application is divided from such prior application.

Referring to the drawing, Figure 1 is a front elevation of a self-closing edgewise movable door with my invention applied thereto. Fig. 2 is a front elevation, on a somewhat larger scale, of the door latch mechanism showing its parts in two of their positions. Fig. 3 is a similar view of the 35 parts in another of their positions. Fig. 4 is a plan view of the door latch mechanism with the parts in the position in which they are shown in Fig. 3. Fig. 5 is a sectional side elevation of a detail of a frictional actuating device which may be used in conjunction with the other parts of the latch actuating mechanism. Fig. 6 is a front elevation of a modified form of the invention.

Like characters of reference designate corresponding parts in all of the figures.

10 designates a sliding door of ordinary construction which is supported upon the rail 11 by means of roller hangers 12 and 13.

Affixed to the door is a horizontally disposed 55 toothed rack 14. An internally threaded

spur-gear 15 is in mesh with this rack at a position at one side of the door opening. The upper and lower surfaces of this gear member are provided with antifriction supporting devices carried by a bracket 16 affixed to a holding block 17 upon the door frame at one side of the door opening.

18 designates a threaded vertical shaft which passes through the internally threaded portion of the gear member so that the latter 60 forms a rotatable nut upon the shaft. This shaft is also supported from the holding block 17. A weight 19 upon one end of this shaft has a tendency to move the shaft downward.

When the door is opened the rack 14 will rotate the gear member 15 and the latter will cause the vertical shaft 18 to be moved upward against the action of gravity. When the door is released the weight 19 will force 75 the vertical shaft downward, thus rotating the gear member 15 and causing the latter, by its engagement with the toothed rack, to close the door.

The mechanism which I have thus briefly 80 described is fully set forth in my prior application for patent to which I have above referred.

The latch which I have invented comprises a latch member 20 which is provided with a 85 slot 21 through which a pin or bolt 22 projects. This pin is affixed to the door and supports the latch member both pivotally and slidably. 23 designates another slot or opening in the latch member through which 90 another pin or bolt 24 affixed to the door projects. The upper surface of the opening 23 is horizontal so that it, with the slot 21, allows the latch member to slide back and forth longitudinally upon the pins 22 and 24 95 a certain limited amount. At the inner end of opening 23 the latch member is cut away as shown at 25 to form a downwardly extending continuation of opening 23. 26 is a curved cam surface at the juncture of the 100 parts 23 and 25 of this opening.

27 is a portion of the latch member which forms a hook upon its outer end. Its inner end is made in the form shown at 28.

28^a is a strap affixed to the door and arranged to support the end 28.

29 is a handle affixed to the latch member 20 or made as an integral projecting part thereof.

30 designates that part of the door frame 110

against which the door is closed. 31 is a latch - receiving member or catch - piece affixed to this portion of the door frame and constructed with a shoulder 32 with which 5 the hook 27 is arranged to engage and with a beveled or grooved portion 33 against which the front end of the hook 27 will strike when the door is being closed.

40 designates a weighted pendant which is 10 pivotally connected with the latch member 20 at 41. A pin 42 which is affixed to the door, passes through a vertical slot 43 in the pendant for a purpose which will appear hereinafter.

15 44 is a horizontally disposed rod pivotally connected with the lower portion of the pendant at 45 and carried across the door and through a fixed bracket 46 through which it is arranged to slide.

20 47 and 48 are collars affixed to the rod 44. The various parts of the invention have been pointed out and I will now proceed with a description of their operation. The hook may be disengaged from the member 31 by 25 being depressed by handle 29. This will cause the latch member to be rotated about the pin 22 until it assumes the position in which it is shown by dotted lines in Fig. 2. From this figure it may be seen that this 30 movement of the latch member will raise the weighted pendant 40 and will cause the portion in which is the opening 25 to be carried up over the pin 24. The slot 43 allows the pendant to make this movement. When in 35 this position the door may be opened and the parts will remain in this position or will resume their first position—that shown in full lines in Fig. 2—until the collar 47 strikes against the bracket 46. The collar and 40 bracket are arranged to arrest further movement of the rod 44, so that as the door 10 is moved further to complete its opening, the rod 44 will push the lower end of pendant 40 forward. As the pendant is pivoted at 42 45 this will cause the latch member 20 to be moved back and the parts will then assume the positions in which they are shown in Fig. 3. The latch member will thus be drawn back and in so that little or none of it projects beyond the edge of the door. The 50 weight of the pendant has a tendency to hold the latch member down in horizontal position. If, however, the operator holds the latch member in its tilted position until the 55 rod 44 acts in a manner above described to move it inward the pin 25 engaging with cam surface 26 will push the latch member down into its horizontal position as the latter moves inward. When the door is again 60 closed the collar 47 will move out of its engagement with the bracket 46 so that the latch member may be moved back into its 65 projecting position. The weight of the pendant 40 has a tendency to produce this result, but in order to insure a positive return of the

parts to the desired positions, the collar 48 is provided on the rod 44 and arranged to engage with the bracket 46 just before the door has reached its closed position. This will cause the pendant to be drawn back to its 70 central position and will force the latch member outward. When the latch member comes in contact with the catch 31 its forward rounded end will abut against the beveled or curved surface 33, and these two 75 parts acting together, will depress the forward end of the latch. The pendant which is raised at the same time and which locks the hook 27 will cause the latter to be raised up behind the shoulder 32 as soon as it has 80 reached the proper position.

In Fig. 6 another form of my invention is shown. Here the latch member 50 is pivoted at 51 to the member 10. 52 is a knob or handle by means of which the latch member 85 may be depressed to disengage it from the catch-piece 31 on the door frame 30. The rear end 53 of the latch member is heavier than that portion of it which is to the left of the pivot 51, so that this part has a tendency 90 to drop down into the position indicated by dotted lines. A cam 54 which is pivoted to the door at 55 is in such a position that it holds up this heavy end of the latch member. The horizontal rod 44 is pivotally attached 95 to the cam below its pivot and is carried across the door and through the bracket 46 as before described. When the door is opened until the collar 47 abuts against the bracket 46 it causes the rod to push the cam 100 over into the position shown in dotted lines in Fig. 6. This allows the latch member to drop down as shown in this figure so that none of it projects beyond the end of the door. In closing the door the parts remain 105 in these new positions until the collar 48 abuts against the bracket 46 and thus arrests further movement of the rod and returns the cam and latch member to their original positions so that the latter will readily engage with the catch-piece 31 when 110 these two parts are brought together.

By the arrangements above described the latch member is removed from its projecting position when the door is open so that the 115 full width of the door opening available for use without the liability of catching and tearing the clothing thereon.

All of the parts of the latch mechanism, except the knob or handle, are preferably 120 placed inside of the door so that they are out of sight and cannot be tampered with. The various parts of the latch mechanism are for convenience mounted upon plates so that the mechanism is complete, self-contained 125 and may be attached to any desired door.

In Fig. 5 a frictional device is shown which is arranged to act upon the rod 44. In this figure 60 designates a ball or roller which is held within a guiding member 61. The 130

lower surface of this guiding member is provided with two planes inclined in opposite directions relative to the upper surface of the rod 44, and the member itself is supported by a bracket 62 which is affixed to the holding plate 17. A spindle 63 projecting upward from the guiding member has a weight 64 upon it. The operation of this device is as follows: Whenever the rod 44 is moved in one direction or the other, the ball 60 will jam between the rod and one of the inclined surfaces of the member to lock the rod to the guiding member 61 and will thereby resist the movement of the rod 44. As soon, however, as this locking effect takes place, the guiding member 61 will be pushed upward against the weight 64 so that the frictional contact between the ball and its guiding member will be released and the rod will be allowed to slide. The result of this action is that the rod 44 will perform its function of pushing the pendant 40 or the cam 54 in one direction or the other as soon as the door is moved in either direction so that the projecting portion of the latch member will be drawn in out of its projecting position as soon as the door is opened slightly and will be returned again to its projecting position when the action of closing the door is commenced.

I have illustrated more than one form of my invention to show that I do not limit myself to any specific form or construction of the parts.

While I have shown my invention applied to a sliding door, it is evident that it is applicable to other types of doors, and one skilled in the art may readily make such mechanical changes as would be necessary to adapt it to a swinging door.

What I claim is.—

1. A sliding door, a latch member therefor projecting beyond the edge of said door, and means actuated by the movement of the door for positively moving said latch member out of its projecting position when the door is opened, and for positively moving said latch member back into its projecting position when the door is closed.

2. A sliding door, a latch member pivotally and slidably mounted upon the door and projecting beyond the edge thereof, a pendant connected with the latch member, and means actuated by the movement of the door for moving the pendant and thereby

causing the pendant to slide the latch member out of its projecting position when the door is opened and to slide the latch member back again when the door is closed.

3. A sliding door, a frame therefor, a latch member pivotally and slidably mounted upon said door and projecting beyond the edge thereof, a weighted pendant connected with the latch member, and a horizontally disposed rod connected with the pendant and with the door frame and arranged to move the pendant and thereby cause the pendant to slide the latch member out of its projecting position when the door is opened and to slide the latch member back again when the door is closed.

4. A sliding door, a frame therefor, a catch-piece mounted upon the frame, a latch member pivotally and slidably mounted upon the door and projecting beyond the edge thereof, a weighted pendant connected with the latch member, a horizontally disposed rod connected with the pendant and with the door frame and arranged to move the pendant and to thereby cause the pendant to slide the latch member out of its projecting position when the door is opened, and means for automatically closing the door, said means being arranged to actuate the pendant through said horizontally disposed rod to move the pendant and cause the pendant to slide the latch member back into its projecting position by the closure of the door.

5. A sliding door, a latch member pivotally and slidably mounted upon the door and projecting beyond the edge thereof, said latch member being provided with a cam surface, a stationary pin engaging with said cam surface and arranged to guide the latch member into the desired position, a pendant connected with the latch member, and means actuated by the movement of the door for moving the pendant and thereby causing the pendant to slide the latch member out of its projecting position when the door is opened and to slide the latch member back again when the door is closed.

In testimony whereof I have signed my name to this specification in the presence of two subscribing witnesses.

WILLIAM KEATING.
